UNITED STATES PATENT OFFICE

GUSTAV LE RUD, OF ARGUSVILLE, NORTH DAKOTA

BELT GUIDE

Application filed September 3, 1926. Serial No. 133,385.

My invention relates to a belt guide which is adapted to provide a means for guiding a belt so that the same will be automatically directed to remain practically central on the 5 pulleys on which the belt is adapted to operate.

A feature of my invention resides in a simple means having an inexpensive nature, yet providing a very effective means of guiding 10 the belt in its operation. The guiding of the belt is practically entirely automatic with my belt guide so that as the operating belt travels over my guide, which may be placed in any convenient position, should the belt 15 in operation tend to slide from one side to the other, my guide automatically directs the same back to a central position in relation to its operation with the pulleys it is operating over.

20 A feature of my invention is in a guide having a frame support or standard provided with a conical pivoted operating member which is mounted upon roller bearings and free to turn on its axis. The standard is 25 adapted to carry the guide cone pulleys which are mounted freely rotatable on their axes and are so positioned as to provide an upwardly inclined annular edge which provides the means for engaging the edge of the belt 30 on either side of the same to direct and automatically center the belt on its operating pulleys.

The construction of my guide is such that the pair of guide cone pulleys are held on 35 the central standard which is free to rotate on its axis and the main frame support for the standard is preferably mounted at an incline so that the whole guide is adapted to set back at an angle to support the guide pulleys in a position to operate more effectively. This incline being in the direction 40 of the travel of the belt.

These features, together with other objects 45 and details of particular construction will be more clearly and fully set forth in the following specification and claims.

In the drawings forming part of my specification:

50 Figure 1 is a plan view of my automatic belt guide.

Figure 2 is a front view of the same.

Figure 3 is a section on the line 3—3 of Figure 2.

Figure 4 is a section on the line 4—4 of Figure 3.

The drawings show the automatic belt 55 guide A as it would appear in operation in the plan view in Figure 1 with the belt B traveling over the same. The belt B rests or contacts with the pulleys 10. The idea 60 is that the guide works automatically by the weight of the belt.

My belt guide A is formed with a base portion 11, which is adapted to support the standard 12 on the roller bearings 13, while 65 a suitable bolt and nut connection 14 hold the standard 12 attached to the base 11. The roller bearings 13 permit the standard to rotate freely in the base 11.

The standard 11 is formed with an upper 70 flat plate like end portion 15 upon which the pulley carrier and supporting member 16 is adapted to rest. The member 16 is provided with flat side walls 17 depending from either side and which are adapted to support the 75 shafts 18 upon which the pulleys 10 rotate. The member 16 is of a V shaped nature and is provided with a depending end having a ball portion 19 formed thereon which is adapted to be held freely in a socket formed 80 in the base portion 11 and by the cover member 20 which extends from the ball 19.

Each of the pulleys 10 are provided with a frustum conical portion 22 which is positioned in a manner on the shafts 18 so as 85 to provide a bearing for the belt B extending in a line above the top of the supporting member 16 and on either side of the same. The outer ends of the pulleys 10 are formed with cylindrical portions 23 which extend 90 angularly from the frustum conical portions 22 in a manner to project, so to speak, upwardly on either side of the side edges 24 of the belt B.

In operation my automatic belt guide A 95 is preferably placed at an inclined angle as is illustrated in Figure 3. Then when the belt B is operating over the guide pulleys 10, should the belt be inclined to move off of its operating pulleys, which are not illus- 100

trated in the drawings, my belt A automatically immediately operates to bring the belt back to the center again and no adjustment is necessary. The guide operates automatically by the weight of the belt and even though the operating pulleys are not in line on a threshing separator, where the wind often shifts the belt to one side, my guide is always in readiness to automatically shift the belt centrally in relation to the operating pulleys.

The upper end 15 of the supporting standard 12 is formed with recess portions 27 on either side, beneath which pin members 28 are adapted to freely engage to hold the supporting member 16 against free disengagement from the apex 26, yet permitting the same to hingedly hook on the apex 26.

The operation is very simple in my guide A as should the belt shift so that the edge 24 will engage the upwardly inclined surface of the portion 23 of either of the pulleys 10, then the standard 12 is rotated slightly while the ball joint 19 limits the rotation and allows just sufficient movement to permit the pulleys 10 to extend at such an angle in relation to the belt B to strike either edge 24 and cause the belt to be moved back to the center automatically.

I provide coil springs 25 extending from the standard 12 and the sides 17 of the pulley supporting member 16, which act to adjust the pulleys 10 and permit a slight hinging movement from the apex 26 of the support 12, thus permitting the pulleys to oscillate on the apex 26 sufficiently to keep the belt in operating contact with the pulleys 10. This construction, together with the bearings 13 and the ball joint 19 permits movement in direction to the guide pulleys 10 so as to most effectively operate the belt B.

My belt guide A operates very effectively owing to its free adjustment and yet limited movement in angular direction so that the guiding of a belt operating on the same is very accurate without requiring adjustment so that all the operation is automatic and in a manner to keep the belt central in relation to the operating pulleys.

I have found my belt to be very desirable for grain separators and other threshing machines where long belts are used and where it is desirable to be sure that the belt is in operation position at all times.

In accordance with the patent statutes I have described the principles of operation of my invention together with the particular formation and construction of the same, of which I desire to represent the best embodiment, and while the drawings show a particular construction and form, I do not wish to confine myself to the same but wish to extend my invention to the scope of the following claims.

I claim:

1. An automatic belt guide including a pair of pulleys, an angular support for said pulleys, operable means by the motion of the belt for rotatably and hingedly supporting said support between said pulleys, and means to limit the transverse shifting movement of the belt guided by said belt guide.

2. A belt guide having an automatic operation by the belt which is operating over said guide including, pulley members having a frusto conical portion, a cylindrical portion extending over said frusto conical portion adapted to form a guiding surface for the sides of a belt, and means located between said pulley members for supporting said pulleys to permit same to be moved as a unit in an angular transverse position.

3. A guide for a belt comprising, a pair of pulleys having a conical portion, a cylindrical portion adjacent said conical portion, means for supporting said pulleys with their axes extending angularly to each other, and means permitting said pulleys to oscillate automatically by the oscillation of the belt transversely and at right angles to said transverse oscillation.

4. An automatic belt guide including, a pair of pulleys, a supporting standard, means for rotatably supporting said standard, and a V shaped supporting member adapted to rest upon said standard to permit the hinging of said V shaped supporting member while said standard can rotate in said supporting means, and means for limiting the degree of rotation.

5. An automatic guide for a belt comprising, a base portion, a rotatable supporting standard held in said base portion, a reduced end portion formed on said standard, a V-shaped hood resting on said reduced end, and shafts extending from each side of said V-shaped hood adapted to support idle pulleys freely and rotatably, said pulleys being moved automatically by the operation of the belt passing thereover so as to engage the side of the belt and cause the belt to be centered.

6. An automatic belt guide including, pulleys upon which the belt is adapted to operate, frusto-conical portions on said pulleys, supporting means for said pulleys adapted to automatically direct said frusto-conical portions to engage the side edge of the operating belt to guide the same in a manner to cause the belt to be automatically centered, said supporting means for said pulleys being disposed between said pulleys and including means to permit an oscillating movement in vertical plane and horizontal plane.

GUSTAV LE RUD.
